US00D984974S

(12) **United States Design Patent** (10) **Patent No.:** **US D984,974 S**
Zhang (45) **Date of Patent:** **** May 2, 2023**

(54) **TELEVISION**

(71) Applicant: **BEIJING XIAOMI MOBILE SOFTWARE CO., LTD.**, Beijing (CN)

(72) Inventor: **Yunlong Zhang**, Beijing (CN)

(73) Assignee: **BEIJING XIAOMI MOBILE SOFTWARE CO., LTD.**, Beijing (CN)

(**) Term: **15 Years**

(21) Appl. No.: **35/513,252**

(22) Filed: **Sep. 14, 2021**

(80) **Hague Agreement Data**

Int. Filing Date: **Sep. 14, 2021**

Int. Reg. No.: **DM/216454**

Int. Reg. Date: **Sep. 14, 2021**

Int. Reg. Pub. Date: **Oct. 1, 2021**

(30) **Foreign Application Priority Data**

Mar. 15, 2021 (CN) 202130137890.1

(57) **CLAIM**

The ornamental design for a television, as shown and described.

DESCRIPTION

1. Television
2. Television
3. Television
4. Television
5. Television
6. Television
- 1.1 : Front
- 1.2 : Back
- 1.3 : Left
- 1.4 : Right
- 1.5 : Top
- 1.6 : Bottom
- 1.7 : Perspective
- 2.1 : Front
- 2.2 : Back
- 2.3 : Left
- 2.4 : Right
- 2.5 : Top
- 2.6 : Bottom
- 2.7 : Perspective

(Continued)

3.1 : Front
3.2 : Back
3.3 : Left
3.4 : Right
3.5 : Top
3.6 : Bottom
3.7 : Perspective
3.8 : Front
3.9 : Back
3.10 : Left
3.11 : Right
3.12 : Top
3.13 : Bottom
3.14 : Perspective
4.1 : Front
4.2 : Back
4.3 : Left
4.4 : Right
4.5 : Top
4.6 : Bottom
4.7 : Perspective

5.1 : Front
5.2 : Back
5.3 : Left
5.4 : Right
5.5 : Top
5.6 : Bottom
5.7 : Perspective
6.1 : Front
6.2 : Back
6.3 : Left
6.4 : Right
6.5 : Top
6.6 : Bottom
6.7 : Perspective
6.8 : Front
6.9 : Back
6.10 : Left
6.11 : Right
6.12 : Top
6.13 : Bottom
6.14 : Perspective

1.1 to **1.7** are views showing a first television; **2.1** to **2.7** are views showing a second television having a protruding top part; **3.1** to **3.14** are views showing a third television having a top part which is in a retracting state in **3.1-3.7** and is in a protruding state in **3.8-3.14**; **4.1** to **4.7** are views showing

a fourth television; **5.1** to **5.7** are views showing a fifth television having a protruding top part; and **6.1** to **6.14** are views showing a sixth television having a top part which is in a retracting state in **6.1-6.7** and is in a protruding state in **6.8-6.14**.

The broken lines in the drawings depict portions of the television that form no part of the claimed design.

1 Claim, 40 Drawing Sheets
